UNITED STATES PATENT OFFICE.

MARCO MARTINI, OF OAKMONT, PENNSYLVANIA.

CALENDAR CLOCK.

Application filed January 2, 1926. Serial No. 78,799.

This invention relates to clocks and more in particular to calendar-clocks.

The primary object of this invention is to produce in a clock a calendar device in which the day and the date of each day are indicated upon a ribbon which is operated by means of a separate mechanism, the operation of which is intermittently governed by a spring-motor of the type usually found in ordinary time-clocks. Another object is the provision of such a calendar device in which the changes of dates are performed instantly at or about midnight. A further object is to provide in such a calendar clock means whereby the used up portion of the date bearing ribbon is led out of the casing, said means having suitable provisions for tearing off the used up portion of said ribbon. Additional features and advantages may appear from the following description considered in connection with the accompanying drawings forming a part of this application, and in which:

Fig. 1 is a front elevation of the operating mechanism and supporting frame-work of my invention, in which view the face of the calendar-clock has been removed for the sake of clearness.

Fig. 2 is a side elevation of the operating mechanism and supporting frame, the latter being shown in section.

Fig. 3 is an enlarged fractional front elevation showing my preferred method of periodically shifting the hour and the minute-dials of the clock.

Fig. 4 is a side view of the hour dial.

Fig. 5 is a side view of the minute dial.

Fig. 6 is a front elevation of a finished calendar-clock built according to my invention, said view also illustrating the relative positions of the calendar-date and time-figures.

Fig. 7 is a diagrammatic perspective view showing the method of intermittently operating the hour and the minute-dials, as well as the calendar by means of a system of cams and levers to be described later.

Fig. 8 shows in perspective a special escapement mechanism used for operating the calendar rolls and ribbon once every twenty four hours for the purpose of changing the date on the calendar-clock.

Fig. 9 is an enlarged view of a detent, or dog, shown in Fig. 8.

Fig. 10 shows in perspective the method of

guiding the unwound calendar-ribbon in a 55 guide-sheath.

Reference being had to the drawings, the calendar-clock mechanism comprises a slightly modified standard, long running, time-clock mechanism indicated generally by 60 the letter T, which mechanism is suitably mounted on the back wall 1 of the clock casing 2. The modification in said mechanism consists in suitably lengthening towards the front of the calendar-clock of the hour-shaft 65 3, the "second"-shaft 4 and the winding-stem 5. At the end of the hour-shaft there is suitably secured the hour operating cam 6 and analogously mounted on the "second"-shaft is the minute operating cam 7; said 70 cams run clockwise and are used respectively to operate the hour dial and the minute dial.

Referring especially to Figs. 3 and 7, the hour dial 8 is rotated in the counter-clock sense indicated by the arrow 9 by means of 75 the following mechanism: A pin 10, adapted to ride over the contour of the cam 6, is secured on a substantially horizontal lever 11, fulcrumed at 12 on the vertical post 13 and guided for vertical rocking movement by the 80 slide 14 provided at the top of another vertical post 15, said posts being secured by means of screws 16 on the cross-brace 17 of the frame-work. At the free end of the lever 11 is rockably secured by means 85 of a pin connection 18 the substantially vertical link 19 to which is also hingedly connected through the pin connection 20 the short horizontal bar 21 the other end of which is rockably supported by the 90 shaft 22 of the hour-dial 8. Upon said bar is pivotally mounted the weighted pawl 23 the tip of which is adapted to engage anyone of the twenty four teeth of the ratchet-wheel 24 which is securely mounted on the shaft 22 95 and to which is riveted the hour-dial 8. The latter is preferably made as light as possible by using very thin material and cutting out all superfluous material. On the front of said dial there are two groups of figures 25 and 100 26 running consecutively from 1 to 12 to indicate respectively the hours of day and night. To differentiate these hours, the ones corresponding to night time may be marked on a black back-ground, as shown in Fig. 3. 105

The rotation in a counterclock sense of the hour-dial is effected as follows: The constantly running hour-shaft 3 with the cam

6 making one full turn every hour gradually and slowly raise the pin 10 and the various connected elements until the time when said pin reaches the highest point of the cam. 5 Upon further rotation of the cam, the pin 10 is caused by the weight of the mechanism proper to drop suddenly from the highest point to the lowest point of the cam. This drop is transmitted by the various elements 10 to the pawl 23 which then compels the ratchet-wheel to advance by one tooth, i. e. one twenty fourth of a revolution, which amount, of course, changes the reading of the dial from one hour to the next following 15 one. If found necessary, and deficiency in the required weight of the lever system to push the dial forward, may be corrected by means of suitable springs, or preferably, by applying a specified weight 27 to the lever 20 11.

The counterclock wise operation of the minute-dial 28 is performed through the agency of a cam and lever system similar in construction to the one just described. A 25 pin 29 rides on the cam 7 and is secured to the lever 30 fulcrumed at 31 on the post 15 and guided in a slide 32 placed on the post 13. The operating pawl 33 is operated in the obvious manner by the highedly connected link 34 and the bar 35, the former being guided in a sleeve 36 positioned on the top of the post 13 and the latter resting freely on the shaft 37 of the minute dial. The operating pawl is also of the weighted 30 type and is adapted to engage the teeth 38 of which there are sixty on the ratchet-wheel 39 to which the dial 28 is secured by means of rivets 40. Owing to the very moderate amount of power which may be derived from the "second"-shaft 4, it becomes still more imperative to reduce the weight of the relatively large minute-dial to a minimum and for that reason it is made of very light gauge material and cut out 45 as much as possible, as suggested in Fig. 3.

The cam 7 makes a full turn every sixty seconds, each turn causes the pawl 33 to shift the ratchet-wheel 39 forward one tooth thereby changing the reading of the minute 50 indicating figures 41 to the next following minute.

To prevent the hour dial and the minute dial from rotating more than the required amount due to the momentum imparted to them by their respective pawls 23 and 33, said dials are preferably subjected to the braking action of the light springs 42 and 43 which bear upon the teeth of their respective ratchet-wheels 24 and 39, and which are suggested diagrammatically in Fig. 7.

All the information pertaining to the daily calendar is printed on a strip or ribbon 44, preferably of paper, which is wound upon a reel 45 rotatively supported by the two parallel arms 46 located at the top of the

main frame 47. This ribbon is guided to travel for a certain distance close and parallel to the inner side of the front 48 by the guide-rollers 49 and 50, and then passes between the traction roller 51 and the friction roller 52, the pressure of which on the traction roller is adjustable by any suitable means, such as the screws 53. The ribbon is then guided outside of the casing by the sheath 54 which extends through the back-wall 1 of the casing and which is provided with a cutting edge 55 whereon the used up portion of the ribbon may be torn off. 70 75

The diameter of the traction roller 51, which effects the required daily unwinding on the ribbon, is such that it will unwind an amount of ribbon equal to the length of the portion corresponding to each day. The power required to move the calendar-ribbon once a day, preferably at or about midnight, is derived from a separate spring-motor 56 whose construction is described later and which transmits its energy to the traction roller 51 by means of a train of suitably proportioned gears represented by the numerals 58, 59, 60 and 61, the latter being secured on the shaft 62 of the traction roller. The speed of rotation of this train is adequately reduced by means of a vane 63 clamped on a shaft 64 rotated by the gears 65 and 66. 90 95 The winding of the spring-motor 56 is performed from the front of the calendar-clock by means of an ordinary socket key applied to a shaft 67 suitably journaled in a support 68 and connected by a set of bevel gears 69 to the winding stem 70 of said spring. 100

Many types of spring-motors are now available in the market for operating the calendar-ribbon. The spring-motor shown in Fig. 1 comprises a stationary spring-housing 95 mounted on the main frame and closed by means of the large gear 58 which is freely mounted on the winding-stem 70 upon which is secured in any desired manner the ratchet-wheel 57. The power-spring 96 has one of its ends riveted to the housing and the other end fastened to the winding-stem 70, and rotation is communicated from the ratchet-wheel 57 to the large gear 58 by means of a pawl 97 which is pivotally mounted on said gear. 105 110 115

As stated before, the power of the latter is made use of but once a day to rotate the traction roller 51 one single turn only. This is obtained by securing on the shaft 22 of the hour-dial a cam 71 of suitable lift upon which a vertically slidable rod 72 is bearing. The latter is guided in the sleeves 73 and 74 mounted on the post 75 and carries intermediate said sleeves the hingedly mounted detent, or dog, 76 which, as shown particularly in Fig. 8 is stopped in its upward swing by a pin 77 driven in the rod 72. This dog has a weight 78 the tendency of which is to 120 125 130

hold the former substantially against the stop-pin 77.

Hingedly mounted upon a bearing bracket 79 fastened to the post 75 is a bell-crank-lever 80 having on its upper arm a nose 81 which is adapted to engage the pin 82 provided in the gear 65. The horizontal arm of said lever is subjected constantly to the action of a compression spring 83 which tends to rotate this lever in a clockwise sense, which motion is limited by the U-shaped stop 84.

It will be noted that, as the cam 71 makes its single rotation every day, it will gradually lift the rod 72 and allow the dog 76 to pass by and above the horizontal arm of the bell-crank-lever 80. At about midnight, the rod drops by its own weight from the highest point on the cam 71 to its lowest point; this causes the dog to strike the bell-crank-lever and rotate it counterclock wise thus releasing the pin 82 and enabling the gear 65, and the traction roll 51, to rotate a full turn, that is, until the pin 82 is again halted by the nose 81 of the bell-crank-lever which by this time has been returned into normal position by the spring 83. The calendar-ribbon is thus moved forward to show another date. This process is, of course, repeated for every day of the year or as long as the calendar-ribbon will last.

In the front of the calendar-clock are, of course, provided the suitably dimensioned and disposed apertures whereby the time and calendar indications may be read. Thus, by referring to Fig. 6, it will be readily understood that the openings 85, 86 and 87 show respectively the dates, hours and minutes, whereas the openings 88 and 89 are provided for winding the time clock and the calendar-springs respectively.

The seconds are indicated in this present embodiment of my invention in the usual manner by means of the stationary dial 90 and the hand 91. In order to enable the removal of the front of the clock without having to pull out the "second"-hand, I prefer to place the "second"-dial on a suitably bent plate 92 secured by rivets 93 to the post 15 (see Fig. 3), said dial being located behind and close to the front 48 and visible through an aperture 94 cut in the front.

As will be understood, as suggested herein, there may be slight changes made in the construction and arrangement of the details of my invention without departing from the field and scope of the same, and I intend to include in this application all such variations, as fall within the scope of the appended claims.

I claim:—

1. In a device for intermittently moving a ribbon, such as the calendar-strip of a clock, the combination of a spring-motor; a moving

means for said ribbon; a train of gears interposed between said spring-motor and said moving means, and an escapement mechanism adapted for intermittently operating said moving means by said spring-motor; said escapement mechanism comprising a pin connected to and rotated by said moving means; a bell-crank-lever normally in locking engagement with said pin; a vertical slidable rod; a dog rockably mounted thereon in such a manner as to break the engagement between said bell-crank-lever and pin on the downward movement of said rod, and means for lifting said rod and subsequently causing the sudden drop thereof.

2. In a device for intermittently moving a ribbon, such as the calendar-strip of a clock, the combination of a spring-motor; a moving means for said ribbon; a train of gears interposed between said spring-motor and said moving means, and an escapement mechanism adapted for intermittently operating said moving means by said spring-motor; said escapement mechanism comprising a pin connected to and rotated by said moving means; a bell-crank-lever; resilient means normally holding said lever into locking engagement with said pin; a vertical slidable rod; a dog rockably mounted thereon in such a manner as to break the engagement between said bell-crank-lever and pin on the downward movement of said rod, and means for lifting said rod and subsequently causing the sudden drop thereof.

3. In a device for intermittently moving a ribbon, such as the calendar-strip of a clock, the combination of a spring motor, a moving means for said ribbon; a train of gears interposed between said spring-motor and said moving means, and an escapement mechanism adapted for intermittently operating said moving means by said spring-motor; said escapement mechanism comprising a pin connected to and rotated by said moving means; a bell-crank-lever; resilient means for normally holding said lever into locking engagement with said pin; means to limit the amount of rotation of the bell-crank-lever toward said pin; a vertical slidable rod; a dog rockably mounted thereon in such a manner as to break the engagement between said bell-crank-lever and pin on the downward movement of said rod, and means for lifting said rod and subsequently causing the sudden drop thereof.

4. In a device for intermittently moving a ribbon, such as the calendar-strip of a clock, the combination of a spring-motor; a moving means for said ribbon; a train of gears interposed between said spring-motor and said moving means, and an escapement mechanism adapted for intermittently operating said moving means by said spring-motor; said escapement mechanism comprising a pin connected to and rotated by said moving

means; a bell-crank-lever; resilient means for normally holding said lever into locking engagement with said pin; means to limit the amount of rotation of the bell-crank-lever toward said pin; a vertical slideable rod; a dog rockably mounted thereon in such a manner as to break the engagement between said bell-crank-lever and pin on the

downward movement of said rod; means to limit the upward rocking movement of said dog on said rod, and means for lifting the rod and subsequently causing the sudden drop thereof.

In testimony whereof I affix my signature.

MARCO MARTINI.
